UNITED STATES PATENT OFFICE.

THEODOR H. MITTENDORF, OF CHICAGO, ILLINOIS, ASSIGNOR TO MID-STATES GUMMED PAPER CO., OF CHICAGO, ILLINOIS, A CORPORATION OF ILLINOIS.

MEANS FOR PROTECTING PORCELAIN AND ENAMELED WARE.

Application filed June 14, 1926. Serial No. 115,723.

My invention relates to means for protecting enameled and porcelain ware, such as bath tubs, wash basins and similar articles during shipment and during their installation in the building.

It is the object of my invention to provide an improved structure for protecting articles of enamel and porcelain ware, which may be easily applied, which will thoroughly protect the article from possible injury due to careless handling during shipping, and during the construction of the building in which they are being installed, and which may be readily removed from the article when it is ready for use.

Other objects will appear from the following description, reference being had to the accompanying drawings in which Fig. 1 is a plan view of a bath tub showing how the protecting covering of my invention may be applied;

Fig. 2 is a perspective view thereof;

Fig. 3 is a transverse vertical cross-sectional view taken on the line 3-3 of Fig. 1 and

Fig. 4 is a developed view of a modified shape of sheet for covering the ends of the top surface of the tub.

In methods usually employed in protecting bath tubs and similar porcelain, enameled and glazed ware, the articles are usually packed in crates, sometimes being first wrapped in paper. This method has the disadvantage that in shipment the paper, which cannot be very securely fastened to the articles because of their irregular shapes is frequently torn from the article. In addition, the methods formerly employed do not protect the article while it is being installed in the building and while the building interior is being finished.

My invention contemplates the use of an unsized gummed paper which is applied to all exposed finished surfaces of the article to be protected. The gum, glue or other adhesive may completely cover one side of the paper, may be applied only in a narrow strip along the edges of the paper, or only at certain spots. The adhesive which is employed is preferably a vegetable product, which does not contain acids or other substances which might stain the surface and which is readily soluble in water, thus permitting the removal of the paper by merely soaking the paper with water. Since the paper is unsized the

water will readily penetrate to and soften the adhesive.

As shown in the drawings, I preferably apply the paper to the article in rectangular strips where this is possible. Such strips 4 are represented as extending from the bottom of the outside of the tub over the top and to the center line of the bottom of the tub. The strips 5 are lapped over the strips 4 and extend over the top of the other side 65 of the tub. It will be noticed that the tub which has been chosen as an illustrative article to which my invention may be applied, is of the type which has a side and one end extending to the floor, upon which it rests, 70 the other end and side lying against walls of the room in which it is installed. The curved end portions of the tub may be conveniently covered with sector shaped pieces 6 of the gummed paper, which extend from the 75 upper rim of the tub to the point A shown in Fig. 1. The pointed ends of these sector shaped pieces 6 are covered by the rectangular pieces 4 and 5 and thus are more securely held in position. The upper horizontal surface of the tub at its ends may be covered with suitable irregularly shaped pieces 7 and 8, which are slit at the edges at which they fold over and extend down into the curved end portions of the tub. The slit portions of these sheet pieces 7 and 8 may be covered by the pieces 6 or may be glued over the top of these pieces. In this manner the various sheets are securely held together to completely and smoothly cover the entire 90 tub.

In the modification shown in Fig. 4 the covering for the ends of the top surface of the tub consists of a rectangular sheet 9 which has a plurality of slits 9^a of varying 95 length cut in one edge so that upon the application of the sheet to the tub, the strips formed between the slits may be easily made to adhere to the warped end surfaces of the tub.

In the use of my invention the article as a tub is moistened and the gummed sheets are applied as above described. The unsized paper readily absorbs any surplus moisture, and thus hastens the drying and setting of 105 the adhesive. The paper covering does not in any way hinder the installation of the tub or its fittings and may remain upon the tub until the building in which it is installed has been completed. Then, by merely spong- 110

ing the paper with water, it may be readily removed.

While I am aware that porcelain fixtures have been covered with shaped or pressed paper and with thick cardboard secured by strips of paste, I am not aware that anyone has employed the combinations of parts set forth in the following claims including relatively narrow strips of unsized paper and an adhesive soluble in water. The paper employed in my protective covering may be conveniently packed in rolls or small flat packages, and by means of a layer of adhesive such paper may be attached to the fixtures so that it will withstand an extraordinary amount of hard usage. At the same time the protective covering may be easily removed by the application of ordinary water which penetrates the unsized paper and dissolves the adhesive, permitting the removal of the covering without the consumption of much time or labor.

While I have shown and described my invention as applied to its use with a bath tub, it will be apparent that the sheets of gummed, unsized paper may be applied to other similar articles by merely varying the shapes of the strips of paper. I, therefore, do not intend to limit my invention to the

method specifically described herein, but 30 wish to limit the scope of my invention only by the claims which follow.

I claim:

1. In a protective covering for porcelain fixtures, the combination of a fixture with a 35 plurality of relatively narrow strips of unsized paper covering parts having curvature in one direction and a plurality of narrow strips of unsized paper of triangular form covering parts having curvature in more 40 than one direction, and a layer of adhesive soluble in water, securing said strips to said fixture.

2. In a protective covering for porcelain fixtures, the combination of a fixture forming a receptacle with a plurality of relatively narrow strips of paper extending from the bottom of said receptacle toward the edge of the same, and a layer of adhesive soluble in water, securing said strips upon said fixture, said paper being unsized whereby water may penetrate to said adhesive to dissolve the same and detach said paper from said receptacle.

In witness whereof, I hereunto subscribe 55 my name this 11 day of June, 1926.

THEODOR H. MITTENDORF.
